BARRETTE

Max M. Hirtenstein, Jamaica, N.Y., assignor to Ben-Hur Products, Inc., New York, N.Y., a corporation of New York

Filed Dec. 23, 1959, Ser. No. 58,787

Term of patent 14 years

(Cl. D86—10)

Fig. 1

Fig. 2

Fig. 3

Fig. 1 is a front elevational view of a barrette, showing my new design.

Fig. 2 is a top plan view as seen from the line 2—2 of Fig. 1.

Fig. 3 is a plan view thereof as it appears in open position and showing the inner sides; and

Fig. 4 is a cross-sectional view taken on the plane of the line 4—4 of Fig. 2.

I claim:

The ornamental design for a barrette, as shown.
